UNITED STATES PATENT OFFICE.

JOSEPH MACECEVIC, OF PITTSBURGH, PENNSYLVANIA.

WRENCH.

1,301,472.

Specification of Letters Patent. Patented Apr. 22, 1919.

Application filed February 26, 1918. Serial No. 219,227.

To all whom it may concern:

Be it known that I, JOSEPH MACECEVIC, a citizen of the United States of America, residing at Pittsburgh, in the county of 5 Allegheny and State of Pennsylvania, have invented certain new and useful Improvements in Wrenches, of which the following is a specification.

This invention relates to certain new and 10 useful improvements in wrenches and designed primarily for use in tightening, loosening and removing nuts which bind or clamp elements employed in automobile engine construction, more particularly nuts 15 not accessible to the ordinary type of wrench and for other purposes wherein the wrench is found applicable, and the invention has for its object to provide, in a manner as hereinafter set forth, a wrench which is simple 20 in its construction and arrangement, strong, durable, efficient and convenient in its use and inexpensive to manufacture.

With the foregoing and other objects in view this invention consists of the novel 25 construction, combination and arrangement of parts, as hereinafter set forth and more specifically described and illustrated in the accompanying drawings wherein is shown an embodiment of the invention, but it is to be 30 understood that changes, variations and modifications can be resorted to which come within the scope of the claims hereunto appended.

In the drawings wherein like reference 35 characters denote corresponding parts throughout the several views:

Figure 1 is an elevation of a wrench in accordance with this invention.

Fig. 2 is a sectional elevation.

Referring to the drawings in detail the 40 wrench comprises a circular head 1, formed with a cylindrical shaft 2, which projects at right angles with respect to the head 1.

The head 1, is formed with a seat or bearing 45 surface 3, and also with a central opening 4.

Mounted upon the bearing or seat 3, and surrounding the shaft 2, is a bevel-gear 5, which revolves about the shaft 2. The gear 50 5, is maintained in position by a washer 6, and a nut 7, the latter engaging with the shaft 2. The gear 5 has a collar 8, against which bears the washer 6.

The collar 8, has its periphery polygonal 55 in contour.

The reference character 9, denotes a sleeve

which provides a socket 10, and the inner face of said sleeve 9, corresponds in contour to the periphery of the collar 8. The sleeve 9, is mounted upon the collar 8, and seated 60 upon the gear 5, and is of greater length than said collar 8, so that the socket formed by the sleeve 9, can receive the nut which is to be tightened, loosened or removed.

Extending through and rotating in the 65 opening 4 of the head 1, is a shaft 11, which has its forward portion projecting from the head 1 and carries a nut 12 and a washer 13. Mounted on the shaft 11, is a pair of collars 14, 15; the latter abuts against the head 1. 70

The shaft 11 projects from a polygonal shaped reduced portion 17 formed on the forward portion of a shank 16. Mounted on the portion 17, is a bevel-gear 18, against which the collar 14 abuts. The gear 18 is 75 formed with a collar 19, seated on the portion 17 and which abuts against a shoulder 20, on the shank 16.

The nut 12 and washer 13 prevents lengthwise movement of the shank 16 and shaft 80 11 in one direction, and movement in the other direction is prevented by the collars 14, 15, these latter also act as a spacing means between the head and gear 18.

The bevel-gear 18, meshes with the bevel 85 gear 5. The shank 16, may be revolved by any suitable means but as shown, by a wrench handle 21.

The collar 8, is designed to receive sleeves 9, of different sizes so as to provide for the 90 use of the wrench in connection with nuts of various sizes.

When the shank 16, is revolved, the gear 18 will revolve the gear 5, the latter carrying the sleeve 9 therewith, and loosening or 95 tightening the nut as the case may be.

What I claim is:

1. A wrench comprising a head, a stationary shaft carried thereby, a gear seated on the head and revolving about said shaft and 100 provided with a collar, means carried by the shaft and engaging with the collar for retaining the gear on the shaft, a nut gripping element detachably connected with the gear by said collar, and revolved by the latter 105 with said gear, a rotatable shank provided with a fixed gear meshing with and driving the first mentioned gear, a shaft projecting from and rotating with the shank and extending through the head, and means carried by the rotatable shaft to prevent lengthwise shifting of the shank. 110

2. A wrench comprising a head, a stationary shaft carried thereby, a gear seated on the head and revolving about said shaft and provided with a collar, means carried by the shaft and engaging with the collar for retaining the gear on the shaft, a nut gripping element detachably connected with the gear by said collar and revolved by the latter with the gear, a rotatable shank provided with a gear meshing with and driving the first mentioned gear, a shaft projecting from and rotating with the shank and extending through the head, means carried by the rotatable shaft for spacing the head from the gear carried by the shank, and means carried by the rotatable shaft to prevent lengthwise movement of the shank. 20
- 5 10 15
3. A wrench comprising a head, a stationary shaft carried thereby, a gear seated on the head and revolving about said shaft and provided with a collar, means carried by the shaft and engaging with the collar for re-
- 25 30

taining the gear on the shaft, a nut gripping element detachably connected with the gear by said collar and revolved by the latter with the gear, a rotatable shank provided with a gear meshing with and driving the first mentioned gear, a shaft projecting from and rotating with the shank and extending through the head, means carried by the rotatable shaft for spacing the head from the gear carried by the shank, and means carried by the rotatable shaft to prevent lengthwise movement of the shank.

In testimony whereof I affix my signature in the presence of two witnesses.

JOSEPH MACECEVIC.
